METHOD OF MAKING BUMPER GUARDS

George Albert Lyon, Allenhurst, N. J.

Application June 4, 1938, Serial No. 211,776

3 Claims. (Cl. 29—152)

This invention relates to bumper guards or impact members, and more particularly to a novel method of making the same.

The usual motor vehicle of the present day is equipped with front and rear horizontally disposed impact members or bumpers in order to protect the car from damage due to accidental collision or sudden blows. The horizontal impact members or bumpers are relatively narrow 5 in width and for that reason it has been found that the bumper of another vehicle or some other object may extend over the bumper thereby rendering the same partially or completely ineffective. For that reason, a large number of motor 10 vehicles of the present day are also equipped with an auxiliary impact member secured to the main impact member or horizontal bumper and which extends vertically upwardly therefrom. It has been found that an extremely effective auxiliary 15 impact member or bumper guard may be stamped or pressed from a piece of sheet metal stock and produced at a minimum manufacturing cost.

It is an object of the present invention to provide a novel method or process of manufacturing 20 impact members and especially auxiliary impact members or bumper guards of the above described type.

It is a further object of this invention to provide a novel process for manufacturing impact 25 members which renders the manufacturing costs extremely low and which provides a resulting product which is rugged and reliable in use.

It is another and further object of this invention to provide a novel method for forming impact members in which at least one fastening tongue is pressed or cut from a central portion of 30 the impact member and bent rearwardly and downwardly for providing a fastening means for detachably securing the impact member to a supporting member.

Another and still further object of this invention is to provide a novel method of making impact members from a flat sheet or strip of metal stock.

A still further object of the present invention is to provide a novel process for making an impact member having a central portion thereof cut away to leave an ornamental portion or insignia at the center of the impact member.

The novel features which I believe to be characteristic of my invention are set forth with particularity in the appended claims. My invention itself, however, both as to its organization, manner of construction, and method of operation, together with further objects and advantages there-

of, may best be understood by reference to the following description taken in connection with the accompanying drawings, in which:

Figure 1 is a front view of the lower portion of an automobile equipped with a horizontal impact member or main bumper bar upon which is mounted an auxiliary impact member or bumper guard;

Figure 2 is an enlarged front elevational view of the auxiliary impact member or bumper guard 10 shown in Figure 1;

Figure 3 is an enlarged rear elevational view of the bumper guard, as shown in Figure 2;

Figure 4 is a plan view of a strip of sheet metal stock from which the auxiliary impact members 15 or bumper guards are being formed, one stamping in Figure 4 being shown as broken or cut away from the main strip;

Figure 5 is an elevational or side view of the sheet metal stock as shown in Figure 4;

Figure 6 is a cross-sectional side view of the auxiliary impact member or bumper guard during an intermediate stage of the process;

Figure 7 is a view similar to Figure 6, showing the finished form of the auxiliary impact member or bumper guard; and,

Figure 8 is a rear elevational view of a modified form of my invention.

I have shown the lower front portion of an automobile or motor vehicle 10 which is equipped 30 with a horizontal impact member or main bumper 11 upon which is mounted an auxiliary impact member or bumper guard 12.

The specific nature and character of the auxiliary impact member or bumper guard 12 may be 35 seen best in Figures 2 and 3 of the drawings. Specifically, the auxiliary impact member or bumper guard 12 includes a lower body portion 13 and an upstanding upper portion 14 which includes a pair of downwardly diverging legs 15 40 and 16 which merge into and form a continuous part of the lower body portion 13. The upper ends of the downwardly legs 15 and 16 merge into a top or apex portion 17.

In order to provide the necessary strength in 45 the leg portions 15 and 16 for withstanding sudden or hard impact blows, the inner and outer edges of each leg 15 and 16 are bent rearwardly into a relatively deep inner and outer flanges 18 and 19. The inner flange 18 of each leg 15 and 50 16 also extends across the upper portion 17 as at 20, and similarly the flange 19 of the legs 15 and 16 extends across the upper portion 17, as at 21.

The lower or main body portion 13 of the auxiliary impact member 12 is shaped to overlie the 55

front face of the main bumper bar 11, which is convexed in the manner provided in substantially all main bumpers of the present day. The main body portion 13 is terminated on its lower end by an obliquely rearwardly and downwardly extending flange 22 which passes directly under the main bumper 11. Apertures which are preferably square in cross-sectional configuration are provided at 23 for the reception of the upper shank portion 24 of the clamping bolt 25.

10 The outer flange 19 of the legs 15 and 16 extends downwardly at its lower end to a point below the top edge of the main bumper 11, as at 26, an intermediate portion 27 thereof being slotted out for the reception of the upper part of 15 the main bumper 11. The portion 26 on each side of the auxiliary impact member 12 thus provide an integral downwardly extending tooth which passes over the back top edge of the bumper 11 and locks the auxiliary impact member 11 20 in place at this point.

Extending downwardly from the upper portion of the lower main body part 13 is an integral fastening tongue 28 which is arranged to extend 25 over the top edge of the main bumper 11 as at 29 (see Figure 7), then directly downwardly, as at 30, to a point just above the lower edge of the main bumper 11 and then obliquely rearwardly and downwardly, as at 31. The oblique lower end 30 portion 31 of the tongue 28 is provided with apertures 32 which are complementary to the apertures 24 in the lower flange portion 22. From an inspection of Figure 3 of the drawings, it will be observed that the clamping bolts 25 extend upwardly through the apertures 24 of the flange portion 22, and through the apertures 32 of the end portion 31 of the tongue 28 into threaded engagement with clamping nuts 33. By virtue of the downwardly extending teeth 26, the tongue 28, the lower flange 22 and the clamping bolts 25, the auxiliary impact member 12 is firmly and securely mounted on the main body bumper 11.

The novel process by which the impact member shown in Figures 2 and 3 is made is illustrated in 45 Figures 4 to 7 of the drawings. In Figures 4 and 5 a strip of sheet metal stock 34 is shown from which the auxiliary impact member 12 is to be cut in the manner as illustrated. The first step of the process includes stamping or cutting a 50 blank 35 from the strip of metal stock 34 of the shape indicated in Figure 4. The blank 35 is substantially the development of the finished auxiliary impact member 12 shown in Figures 2 and 3. The dash-dot lines shown on the blank at 55 the extreme right side of Figure 4 indicate the subsequent lines of bend to be carried out in the subsequent steps of the process. As is clearly shown in Figures 4, two diverging lines of cut A and B are made in the upper central portion 60 of the blank to define the legs 15 and 16 and to provide the tongue 28. A small area of metal, indicated by the reference numeral 36, is completely cut out of the blank, since that portion 65 is not needed in the completed tongue 28. During the same operations by which the blank 35 itself is cut or stamped and the lines of cut A and B are made, the apertures 23 and 32 are also formed. The next step of the process is to press, roll, or otherwise form the flanges 18 and 19 and 70 to shape the tongue 28 into the form shown in Figure 6. This is preferably done in a single stamping operation. During this same stamping operation, the body part 13 is given its final configuration and the lower obliquely turned body 75 flange portion 22 is also formed.

In the final stage of the process, the tongue 28 is bent over from its position as shown in Figure 6 to its position as shown in Figure 7. The auxiliary impact member 12 may now be given any suitable ornamental appearance, such as by providing the outer surface thereof with a high polish. Thereafter, the auxiliary impact member 12 is ready to be mounted on either the front or rear main impact member or bumper of a motor vehicle.

In Figure 8 of the drawings, I have illustrated 10 a modified form of my invention wherein an ornamental insignia 37 is provided in the space between the two diverging legs 15 and 16. As shown, the ornamental insignia 37 has two downwardly converging legs 38 which are connected together 15 at intermediate portions thereof by curved cross-members 39 and 40. The exact nature and character of the insignia 37 may be varied through wide limits without departing from the spirit and scope of the present invention.

In making the auxiliary impact member, as shown in Figure 8, two tongues 41 and 42 are stamped and pressed from the central portion of the impact member 12. By making four lines of cut in the central portion of the impact member blank instead of two, two tongues 41 and 42 are provided and simultaneously, the integral central portion 37 is also provided. The portion 43 above the central insignia portion 37 may be cut out if desired. In all other respects, the auxiliary impact member 12 of Figure 8 is substantially the same as the auxiliary impact member 12 of Figures 2 and 3 and is mounted on the main bumper 11 in substantially the same manner. The integral teeth 26 are hooked over the top edge of the bumper, and the tongues 41 and 42 are also hooked over the top edge of the main bumper 11. Thereafter, the lower base flange 22 is rocked into position under the lower edge of the main bumper 11 until the main body portion 13 intimately overlies the front face of the bumper 11. Clamping bolts 25 are now passed through the base flange 22 and through the lower ends of the tongues 41 and 42 and the clamping nuts 33 are thereafter threaded onto the threaded shanks of the bolts 25 45 thereby securely fastening the impact member 12 on the vehicle bumper 11.

From the above description, it will be apparent that I have provided an extraordinarily simple method and means for manufacturing impact 50 members from sheet metal stock. It will, furthermore, be observed that this novel process is extremely economical and provides a resulting product which is rugged and reliable in use.

While I have shown particular embodiments 55 of my invention, it will, of course, be understood that I do not wish to be limited thereto, and I therefore contemplate by the appended claims to cover all such modifications as fall within the true spirit and scope of my invention.

I claim as my invention:

1. The method of making sheet metal impact members which includes stamping a blank from a piece of sheet metal stock, said blank having an upper triangular section to be formed into an impact portion and a lower body section for overlying the front face of a vehicle bumper, making a pair of inverted V-shaped cuts in the upper triangular section, thereby to provide two integrally joined diverging legs which merge into 70 said lower body section, a centrally disposed insignia portion and a pair of integral tongues, thereafter bending the marginal portions of said legs rearwardly to form stiffening flanges and bending said tongues rearwardly and downwardly 75

in spaced relationship to said body section thereby to provide fastening arms for hooking over the vehicle bumper and for extension across the rear face thereof.

5 2. The method of making sheet metal impact members which includes stamping a blank from a piece of sheet metal stock, said blank having an upper triangular section to be formed into an impact portion and a lower body portion for overlying the front face of a vehicle bumper, said upper triangular section including a pair of downwardly extending wings at the opposite lower corners thereof, making two diverging lines of cut in the upper triangular section substantially parallel 10 to the outer edges of said section, thereby to provide two integrally joined diverging legs which merge into said lower body section and which further provide a centrally disposed integral tongue integrally joined to said lower body section, bending the marginal side portions of said legs rearwardly to form stiffening flanges, bending the lower marginal edge portion of said lower body section obliquely rearwardly and downwardly for extension below the vehicle bumper, 15 and bending said tongue rearwardly, downwardly through a distance slightly less than the width of the vehicle bumper, and then obliquely rearwardly and downwardly, said wings of said blank being adapted to hook over the top of the vehicle 20 bumper and to extend into engagement with the

rear side thereof, and said obliquely rearwardly extending portions being arranged to be detachably connected together for firmly securing the impact member to a vehicle bumper.

3. The method of making a sheet metal auxiliary impact member for a vehicle bumper which includes stamping out a blank, said blank having an upper section of the general shape of an isosceles triangle and a lower section extending from the base of said triangle and of the general shape 5 of a rectangle, the lower corners of the upper section extending out beyond the ends of the lower section and being cut by the stamping operation into hooks extending down alongside said lower section, making a generally inverted V-shaped cut 10 in said upper section substantially parallel to the sides thereof to form a flap, bending back the side edges of said upper section to form an exterior flange terminating at its ends in said hooks, said hooks being thereby swung around in back of the 15 plane of said lower section, simultaneously bending back the inner edges of the portions of said upper section lying outside of said cut and the portion of the upper edge of said lower section 20 lying between the lower ends of said cut to form 25 a continuous flange extending around a triangular opening defined by said cut and said upper edge of said lower section, and finally bending said flap down behind said lower section.

GEORGE ALBERT LYON. 30
